UNITED STATES PATENT OFFICE.

CONRAD M. CONRADSON, OF MILWAUKEE, ASSIGNOR TO THE GISHOLT MACHINE COMPANY, OF MADISON, WISCONSIN.

PULLEY.

SPECIFICATION forming part of Letters Patent No. 429,507, dated June 3, 1890.

Application filed January 8, 1890. Serial No. 336,298. (No model.)

To all whom it may concern:

Be it known that I, CONRAD M. CONRADSON, a citizen of the United States, and a resident of Milwaukee, in the county of Milwaukee and State of Wisconsin, have invented certain new and useful Improvements in Pulleys; and I do hereby declare that the following is a full, clear, and exact description of the invention, which will enable others skilled in the art to which it appertains to make and use the same.

My invention relates to improvements in pulleys, the object being the production of a pulley which will be self-lubricating, and which will possess merit in point of simplicity, durability, and inexpensiveness, and which will be thoroughly efficient in its operation.

The invention consists, broadly stated, of a pulley having a reservoir, a sleeve or bushing fitted in the bore of the pulley and having openings communicating with the reservoir of the pulley, and a sleeve or bushing fitting in the first-mentioned bushing having oil-passages and adapted to revolve on the shaft or with the same.

The invention also consists in the novel construction and combination of the parts of the pulley, substantially as illustrated in the drawings, and described and claimed herein-after.

Figure 1 represents a vertical central section of a pulley constructed in accordance with and embodying my invention. Figs. 2, 3, and 4 represent similar views of the parts of the pulley detached.

Referring by numerals to the drawings, in which the same numerals designate corresponding parts in the several figures, the numeral 1 designates the pulley proper, formed with a reservoir 2, in this instance substan-

tially oval-shaped, and provided with a filling-opening 3, closed by a vent-plug 4.

Within the bore of the pulley is fitted a sleeve or bushing 5, having oil-feeding openings 6, communicating with the reservoir of the pulley, and in said sleeve 5 is fitted a sleeve or bushing 6', having longitudinal oil-passages 7, and said sleeve 6' may be loose in the sleeve 5 and form the bearing therefor, or it may be fast and revolve with the pulley 50 on the shaft, as may be desired.

The numerals 6² designate a series of circumferential oil-passages in sleeve 6', communicating with the openings 6³, by which the feeding of the oil is facilitated.

From the foregoing it will be seen that I provide a self-oiling pulley which is thoroughly effective for the purpose intended, and one which possesses numerous advantages over pulleys in general use, as will be readily understood and appreciated by all skilled in the art.

Having thus described my invention, what I claim as new, and desire to secure by Letters Patent, is—

A pulley having a reservoir 2, a bushing or sleeve fitted in said pulley and having openings 6 communicating with reservoir 2, and a bushing or sleeve 6' fitted in said first-named sleeve and having openings 6³, longitudinal oil-passages 7, and circumferential oil-passages 6², substantially as described.

In testimony that I claim the foregoing as my own I have hereunto affixed my signature in presence of two witnesses.

CONRAD M. CONRADSON.
